BYRON B. PHILLIPS, OF HUDSON, NEW YORK.

ICE-CONVEYER.

1,209,021.

Specification of Letters Patent. Patented Dec. 19, 1916.

Application filed March 29, 1916. Serial No. 87,580.

To all whom it may concern:

Be it known that I, BYRON B. PHILLIPS, a citizen of the United States, residing at Hudson, in the county of Columbia and 5 State of New York, have invented a new and useful Ice-Conveyer, of which the following is a specification.

This invention has reference to ice conveyers, and its object is to provide a conveyer for removing ice from storage rooms 10 or for other purposes to which the invention may be applied.

In accordance with the present invention the conveyer is made up of a number of 15 separate sections each complete in itself and adapted to be connected at the ends to other like conveyer sections, so that power applied to one conveyer section is transferred through all the connected sections. Each 20 section is provided with means for engaging the ice or other material to be conveyed and the engaging means of any section may be moved into or out of active or engaging relation to the material to be moved without 25 affecting other sections. In this manner the conveying of the ice or other material may begin at any section and continue through any chosen number of sections.

While the invention is adaptable for conveying various materials, it is designed primarily for moving ice from storage rooms, wherefore, for simplicity of description, the 30 following description will be confined to the use of the invention for ice conveying without 35 out, however, thereby confining the invention to such particular use.

The invention will be best understood from a consideration of the following detailed description, taken in connection with 40 the accompanying drawings forming part of this specification, with the further understanding that while the drawings show a practical form of the invention, the latter is not confined to any strict conformity with 45 the showing of the drawings, but may be changed and modified so long as such changes and modifications come within the scope of the appended claims.

In the drawings: Figure 1 is a plan view 50 of a portion of an ice conveyer made up of a plurality of sections joined end to end. Fig. 2 is a section on the line 2—2 of Fig. 1 but drawn on a larger scale. Fig. 3 is a section on the line 3—3 of Fig. 1 but drawn 55 on a larger scale. Fig. 4 is a section on the

line 4—4 of Fig. 1 but drawn on a larger scale.

Referring to the drawings, there is shown a series of conveyer sections A, B, C, which may be considered as representative of any number of conveyer sections abutted end to end to provide an elongated conveyer of the desired length. Each section of the conveyer comprises a frame made up of side bars 1 and cross bars 2. The side bars 1 are shown as angle bars each of a length corresponding to the length of the section, and the cross bars 2 are each of suitable size having rising bends 3 adjacent to the side bars. The bends 3 support angle tracks 4 with the angle uppermost and designed to support blocks of ice placed upon them, such tracks constituting both supports and guides for the blocks of ice moved lengthwise of the conveyer. The angle edges of the tracks 4, which angle edges are indicated at 5, may slightly embed themselves in the blocks of ice, whereby lateral movements of the blocks when moving along the tracks is prevented and the blocks of ice, therefore, may be transported along the conveyer without liability of leaving the tracks.

The frame members and tracks of each conveyer section are riveted or otherwise secured together, so that the section is in effect of unitary construction. Extending lengthwise of each section between the tracks 4, and preferably midway between the tracks 4, is a boxing 6 shown as composed of channel strips 7 and angle strips 8 with the channel strips 7 carried by the cross bars 2 above the latter and the angle strips 8 carried by the cross bars 2 with depending matching webs spaced apart a sufficient distance, the channels 7 being correspondingly spaced and rising to a height above the bars 2 which may be a little less than the height of the edges 5 of the tracks 4 above the main portions of the bars 2. If the blocks of ice are entered sufficiently by the edges 5 of the tracks 4, the middle portions of the blocks may rest upon the top flanges of the channels 7, which flanges extend oppositely one from the other toward the respective tracks 4. Journalled in the boxing thus formed, near respective ends of the boxing, are shafts 9, 10, respectively, with the shaft 9 carrying a sprocket wheel 11 and the shaft 10 carrying a sprocket wheel 12. The sprocket wheels are located in the boxing 110

between the walls thereof and traveling about the sprocket wheels with runs extending from one sprocket wheel to the other is a sprocket chain 13 carrying spurs 14 or 5 other suitable engaging devices. The spurs 14 answer very well for ice, but for other articles other appropriate engaging means may be provided.

In the operative position of the conveyer 10 sections they are laid either horizontally or at inclines, so that there is an upper run 15 and a lower run 16 of the conveyer chain. Each upper run is supported by a T bar 17 of a length somewhat less than the distance 15 between the sprocket wheels 11 and 12 with the stem of the T extending downwardly and suitably recessed at the ends, as shown at 18 and 19, respectively, to engage the upper surfaces of certain ones of the cross bars 20 2 to permit certain movements of the bar 17.

Secured to the inner faces of the depending webs of the angle bars 8 are angle strips 20 with webs directed one toward the other in position to support the lower run 16 of 25 the chain 13, this chain being of a length to have its lower run sag somewhat when the upper run is about straight or supported by the T bar 17 when the latter is close to the cross bars 2.

30 Provision is made for elevating the T bar 17, that is, for moving it toward the upper open side of the boxing, in which case the upper run 15 of the chain 13 is correspondingly lifted and the spurs 14 are correspondingly lifted. The movement of the bar 17 with the upper run 15 of the chain is such that in the lowered position of the bar the spurs are housed within the boxing and when the T bar 17 is elevated the spurs are 40 projected above the top of the boxing.

In order to provide for the elevating and lowering movements of the bar 17, each section of the conveyer has near one end a transversely arranged crank shaft 21 journaled in the boxing and in one of the side bars 1 of the conveyer section frame, the shaft having a crank portion 22 located within the boxing. This crank 22 is connected by a link 23 to the corresponding end 50 of the end portion of the bar 17. That end of the crank shaft 21 which projects through one of the side bars 1 has a squared end 24, or is otherwise arranged for the application of a crank or other operating device, where- 55 by the shaft 21 may be rocked through a sufficient distance for the purpose of the invention. The bar 17 is carried at suitable intervals by links 25 each pivoted at one end to that portion of the boxing represented by 60 the angle bars 8 and at the other end to the stem web of the bar 17. The links 25 may be arranged in pairs with the links of each pair on respectively opposite sides of the bar 17. When the bar 17 is in the lower position the links 25 are inclined with respect

to the longitudinal center line of the conveyer section, and when the bar 17 is in the elevated position these links are or may be substantially perpendicular to such longitudinal center line, the links moving about 70 their pivot connections with the angle bars 8, such pivot connections being indicated at 26. The pivot connections of the links 25 with the bar 17, which pivot connections are indicated at 27, move on an arc about the 75 pivots 26. The result is that the spurs 14 are projected above the top of the boxing sufficiently to enter the bottom faces of the cakes of ice which may at the time be upon the tracks 4. Each shaft 9 carries a gear wheel 28 to one side of the boxing which may there be provided with a face plate 29. Each shaft 10 carries a similar gear wheel 30 also outside of the boxing, which is there provided with a face plate 31 similar to the 85 face plate 29. The gear wheel 30 meshes with an idler gear wheel 32 carried by the face plate 31 and projecting beyond the end of the face plate 31 and the corresponding end of the conveyer section sufficiently to 90 mesh with the gear wheel 28 on the shaft 9 of the next conveyer section in order. By this means when the conveyer sections are placed in end to end engagement the idler gear wheel 32 at one end of one of the conveyer sections meshes with the gear wheel 28 of the next conveyer section in order, wherefore when a conveyer is installed with the sections connected end to end and power is applied to one of the shafts, say, a shaft 9, 100 to cause the conveyer chain 12 of such shaft to travel, all the other conveyer chains are similarly set in motion. The mere act of placing the conveyer sections in end to end engagement accomplishes the automatical 105 coupling of the movable parts of the conveyer together, so that if power be applied to the propelling means of some one conveyer section, the propelling means of all the other conveyer sections of the series thus 110 produced receive motion from the one to which power is directly applied. If the crank shaft 21 of each conveyer section be in such position that the chain controlling bar 17 is in the lowered condition, then all the 115 spurs 14 are inactive because withdrawn into the central boxing 6, and while the conveyer may contain cakes of ice, the latter are not then propelled by the conveyer chain, although, of course, if the conveyer section 120 be then inclined it may then serve as a skid for the ice.

While all the conveyer chains are at the time in motion, any one of them may be put into active relation to the material being 125 conveyed irrespective of any other conveyer chains in the same series. This is accomplished by manipulating the respective shaft 21 to elevate the bar 17, thereby correspondingly elevating the upper run 15 of the 130

- chain 13 and projecting the spurs 14 belonging to such chain. Any cakes of ice which may at the time be upon such conveyer section are then propelled by the particular 5 active one of the conveyer chains, and any blocks of ice which may be upon the conveyer sections ahead of the active one in the line of travel are pushed forward by those blocks engaged by the active conveyer chain.
- 10 In this manner ice may be conveyed from various parts of a storage room at the will of the operator, and any one or more of the conveyer chains may be rendered active or inactive to the blocks of ice, as may be desired.

The spurs or prongs 14 which of course may be replaced by carrier bars or other means to engage the ice or other articles are so arranged as to be housed in the boxing 20 or rendered inactive to the material being conveyed or projected into active position at the will of the operator. The bar 17 serves both as a means for elevating and lowering the active run of the chain, and 25 as a support for the chain between the sprocket wheels over which the ends of the runs of the chain move. To provide for the elevation and depression of the upper run of the chain, the latter is made somewhat 30 loose between the sprocket wheels, and it is for this reason that the under supports 20 for the under run of the sprocket chain are provided in order that the chain may not when in the inactive position sag below the 35 box 8 and the latter need not be made deep enough to provide for such a degree of sagging of the lowered run of the chain.

What is claimed is:—

1. A conveyer provided with track means 40 for the support of articles to be conveyed, propelling means for the articles, and means for moving the propelling means into and out of operative relation to articles on the track means, at will.
- 45 2. A conveyer comprising a plurality of sections each having tracks for the support of the articles to be conveyed, propelling means for such articles, and means for moving the propelling means into and out of operative relation to the articles on the 50 tracks at will, the propelling means of each section having means for automatically coupling it to the propelling means of the next section or sections in order.
- 55 3. A conveyer section comprising a frame, tracks mounted thereon in spaced relation, propelling means for articles carried by the tracks, and means for moving the propelling means into and out of engagement with 60 articles on the tracks, at will.
4. A conveyer section comprising a suitable frame, spaced tracks mounted thereon, a boxing on the frame between the tracks, an endless propelling means mounted in the 65 boxing and provided with means for engag-

ing articles on the tracks, and means for projecting the propelling means from the boxing into engaging relation to articles on the tracks or to withdraw the propelling means into the boxing, at will.

5. A conveyer section comprising a suitable support, tracks mounted on the support, a boxing also mounted on the support, an endless chain in the boxing provided with engaging means for articles upon the tracks, carrying means for the chain located within the boxing, and means for moving the chain to project the engaging means from the boxing or to draw it into the boxing, at will.

6. A conveyer section, comprising a suitable support, tracks mounted thereon for articles to be conveyed, a boxing on the support between the tracks, an endless chain mounted in the boxing and provided with engaging members for the articles to be 85 conveyed, a support for the upper run of the chain, and means for elevating or lowering the support to correspondingly elevate or lower the chain to project the article-engaging means from the boxing or withdraw them into the boxing, at will.

7. A conveyer section comprising a suitable frame, tracks mounted thereon, a boxing on the frame between the tracks, sprocket wheels mounted in the boxing between the ends thereof, an endless sprocket chain engaging the sprocket wheels and provided with engaging means for the articles to be conveyed, a support for the upper run of the chain, and means for moving the support to project the engaging devices on the chain or withdraw them into the boxing, at will.

8. A conveyer section comprising a suitable frame, tracks mounted thereon, a boxing on the frame between the tracks, sprocket wheels mounted in the boxing between the ends thereof, an endless sprocket chain engaging the sprocket wheels and provided with engaging means for the articles to be 105 conveyed, a support for the upper run of the chain, and means for moving the support to project the engaging devices on the chain or withdraw them into the boxing, at will, the conveyer section having gear wheels thereon 110 connected to the respective sprocket wheels and the gear wheel at one end of the section having an idler gear wheel in mesh therewith to engage a gear wheel of a neighboring section to transmit power from one 115 sprocket chain to the next in order in a series of assembled sections.

9. A conveyer section for assemblage in a series of sections making up a conveyer, comprising a suitable elongated frame, tracks mounted on the frame, a housing on the frame between the tracks and of substantially the length of the section, sprocket wheels mounted in the housing near the ends thereof, an endless sprocket chain mounted 125 130

on the sprocket wheels, engaging members on the sprocket chain for articles supported by the tracks, gear wheels connected to the respective sprocket wheels for transmitting power from one sprocket chain to the next in order in an assembled series of sections, and means for projecting one run of the chain from the boxing for engagement with the articles to be conveyed or withdrawing it into the boxing to permit movements of the chain without engagement with such articles.

10. A conveyer section comprising a suitable frame, tracks mounted thereon, a boxing also mounted on the frame between the tracks, an endless chain in the boxing having engaging devices for the articles to be conveyed when on the tracks, an elongated bar in under-riding relation to the upper run of the chain, pivoted links carrying the bar for the elevation and lowering of the bar by a longitudinal movement thereof, and means for effecting such longitudinal movement of the bar, at will.

15. 11. A conveyer section comprising a suitable frame, tracks mounted thereon, a boxing also mounted on the frame between the tracks, an endless chain in the boxing having engaging devices for the articles to be conveyed when on the tracks, an elongated bar in under-riding relation to the upper run of the chain, pivoted links carrying the bar for the elevation and lowering of the bar by a longitudinal movement thereof, and means 20 for effecting such longitudinal movement of the bar, at will; said conveyer section also being provided within the boxing with supporting means for the lower run of the chain.

25. 12. A conveyer section comprising a suitable frame, tracks mounted thereon, an

elongated boxing between the tracks, an endless chain within the boxing and provided with engaging means for articles on the tracks, a support for the upper run of the 45 chain comprising an elongated bar in under-riding relation to said upper run, and pivoted links carrying the bar, and means for moving the bar lengthwise on the pivot links comprising a crank shaft with accessible 50 means for its manipulation, and connections between the crank shaft and bar.

13. A conveyer section comprising a suitable frame, tracks mounted thereon, an elongated boxing between the tracks, an endless 55 chain within the boxing and provided with engaging means for articles on the tracks, a support for the upper run of the chain comprising an elongated bar in under-riding relation to said upper run, and pivoted links 60 carrying the bar, and means for moving the bar lengthwise on the pivot links comprising a crank shaft with accessible means for its manipulation, and connections between the 65 crank shaft and bar, the boxing being provided with supporting wheels for the chain near the ends of the boxing, a gear wheel connected to each supporting means, and an idler gear wheel connected to the gear wheel at one end of the boxing and extending beyond the corresponding end of the boxing to engage a neighboring gear wheel on a neighboring section in an assembled series of conveyer sections.

In testimony that I claim the foregoing as 75 my own, I have hereto affixed my signature in the presence of two witnesses.
